UNITED STATES PATENT OFFICE.

BANCROFT G. BRAINE, OF NEW YORK, N. Y., ASSIGNOR TO THE CONTINUOUS RAIL JOINT COMPANY OF AMERICA, OF NEW JERSEY.

DESIGN FOR A GIRDER CONNECTION FOR GIRDER-RAILS IN STREET-RAILWAYS.

SPECIFICATION forming part of Design No. 30,419, dated March 28, 1899.

Application filed January 30, 1899. Serial No. 703,903. Term of patent 14 years.

To all whom it may concern:

Be it known that I, BANCROFT G. BRAINE, a citizen of the United States, residing at the borough of Brooklyn, in the city of New York and State of New York, have invented and produced a new and original Design for a Girder Connection for Girder-Rails in Street-Railways; and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

The single figure of the drawing shows in endwise a girder connection of my new design and is thought to sufficiently illustrate the invention.

The leading or material feature of my new design consists in a girder connection for girder-rails in or of a street-railway having the configuration as follows, to wit:

The vertical body portion *a* is of substantially uniform thickness from near the upper edge to the lower part. At said lower part

the plate-like body is bent outward, as at *b'*, the outwardly-extending part being disposed at an incline and at its outer end extending more abruptly downward, as at *b²*, and being returned, as at *b³*, the returned part lying in a horizontal plane. The upper edge of the body portion is enlarged or head-shaped, viewed endwise of the connection, as in the drawing, the head-shaped part projecting outwardly and inwardly from the vertical axial plane of the said body portion and at its upper side or top being beveled or inclined downward in a direction opposite to the direction of projection of the part *b'*.

What I claim as new is—

The design for a girder connection for girder-rails in street-railways, as herein shown and described.

In testimony that I claim the foregoing I have hereunto set my hand this 6th day of January, 1899.

BANCROFT G. BRAINE.
